To all whom it may concern:

Be it known that I, JOHN H. My invention relates to the surface ornamentation of Brussels and other carpets, and consists of the pattern for body and border illustrated in the annexed drawing, in which the body A of the carpet consists of a plain ground filled in with small octagonal line figures a and ornamented by rosebuds interspersed, some being single buds and leaves as at b, and some double as at c. The border B has three parallel lines of figures d, d', d² denoting its edges, and between two of them a straight string h of leaves and buds, and between the other two a curved or festooned string m of leaves and buds suspended at ends from a bow-knot n.

I claim—
